BENJAMIN Q. ISLER, OF NEW YORK, N. Y., ASSIGNOR, BY MESNE ASSIGNMENTS, TO
LAZARUS SHAPIRO, OF NEW YORK, N. Y.
VARIABLE CONDENSER.

Application filed August 8, 1922. Serial No. 580,491.

This invention relates to an electrical condenser, and more particularly to a variable condenser, and has special reference to the provision of an improved variable condenser, in which simplicity of manufacture, ease of assembly, efficiency of operation, strength, compactness and neatness are combined and attained to a relatively high degree.

One of the principal objects of my present invention comprehends the provision of a variable condenser of the type in which variation of capacity is obtained by changing the capacitive relation between stationary and movable plate sets, in which an accurate setting of the movable plate set for producing sharp and exact tuning may be obtained and in which a given setting will invariably correspond with a given capacity. A common form of condenser of the type referred to comprises a rotatable plate set or set of plates including a shaft journalled in end bearings and insulately mounted with respect to a stationary set of plates. A number of methods of journaling the rotatable set of plates have been employed in prior condensers of this type, a common and approved method including the provision of fixed or adjustable cylindrical bearings for the shaft and a resilient element or spring take up at one end thereof functioning to position the movable set of plates in properly spaced, alternating relation with respect to the stationary set of plates, and to take up end play of the movable set of plates. Although in prior strong and durable resilient supporting condensers in which this method is employed end play is in effect taken up, and automatically compensated for during rotation of the movable plate set, I have found that a serious defect or fault in such condensers resides in the fact that no provision is made for eliminating or taking up lateral play of the movable plate set, with the result that accuracy of setting to obtain a desired capacity for sharp tuning cannot be obtained.

Where conical fixed or adjustable bearings without resilient take up means are employed, the same objection is presented, and while axial and lateral play may be taken up by adjustment at one setting of the condenser, such play is found relatively pronounced at another setting of the same, inaccuracy of machining of the bearing parts, slight eccentricities of mounting or set resulting particularly from quantity pro-

duction methods contributing in a large measure as causes for the presence of such defect. I have found that when lateral play of the rotor shaft is not compensated for, that the looseness of the shaft in an end bearing results in a rolling motion of the same in the bearing during rotation in both directions of the rotor plate set, so that a given capacity does not invariably correspond with a given setting of the movable plates and so that movement of the movable plate set to obtain a given setting is attended with considerable uncertainty and difficulty. A principal object of the present invention, therefore, relates to the provision of a condenser construction in which lateral play and longitudinal play are simultaneously and automatically taken up at all settings of the condenser, with the result that a given setting accurately and repeatedly corresponds with a given capacity and sharp and accurate tuning is made possible.

The principal objects of the invention may be said to include, besides the provision of a condenser having the characteristics and capable of performing the functions above mentioned, the further provision of a condenser in which conically shaped and resiliently mounted bearings for the rotor shaft are combined to eliminate the lateral and longitudinal play of the shaft at all times; the further provision of resilient means for supporting the movable plate set to produce a movable set of plates integral with the rotor in spite of the space restrictions or limitations presented; the further provision of improved means for electrically connecting the movable plate set to a connecting terminal; the still further provision of a condenser in which the plate sets are made integral to simplify the manufacture of the condenser parts, and in which the integral plate sets are cast into an integral unit in a novel and improved manner; the still further provision of a condenser in which the plates of each plate set are shaped while axial and lateral play may be taken up to provide for a desirable calibration curve of the condenser with a minimum sacrifice of space economy; and the still further provision of a condenser of this nature in which the parts are provided with inter-registering means to facilitate assembly and to permit accuracy of registration and positioning of the parts while effectively permitting com-

pensation for any differential expansion or contraction between the parts taking place during the process of manufacture.

To the accomplishment of the foregoing and such other objects as may hereinafter appear, my invention consists in the elements and their relation one to the other, as herein-after particularly described and sought to be defined in the claims, reference being had to the accompanying drawings which show preferred embodiments of my invention and in which:

Fig. 1 is a cross-sectional elevational view of my improved condenser;

Fig. 2 is a front elevational view thereof;

Fig. 3 is a plan view thereof showing my improved resilient supporting means therefor;

Fig. 4 is a view taken in cross-section on the line 4--4, Fig. 1;

Fig. 5 is a cross-sectional elevational view of a modified form of the condenser;

Fig. 6 is a bottom plan view of the same with parts broken away;

Fig. 7 is a top plan view of the same;

Fig. 8 is a view showing a preferred modification of the manner of mounting the rotatable plate set;

Fig. 9 is a view showing a construction utilized in an improved manner of casting the rotatable plate set;

Figs. 10 to 13 inclusive are views showing the manner in which interregistration of the parts may be obtained while compensating for any differential contraction in such parts taking place during the process of manufacture, and

Fig. 14 is a fragmentary cross-sectional view showing a modification.

As heretofore referred to, one of the principal objects of the invention comprehends the provision of a variable condenser in which the capacity is always uniform for a given setting, with accuracy and sharpness of tuning thereby made possible. To this end the invention includes the provision of means for so mounting the movable plate set with respect to the stationary plate set that lateral as well as axial play of the movable plate set is automatically and simultaneously taken up in the movement of the same. Where the condenser is of the type in which the movable plate set constitutes a rotor and the stationary plate set constitutes a stator, the invention includes the mounting of the rotor shaft in conical and resilient end bearings in such a manner that the shaft is continuously resiliently urged against and seated in the end bearings with lateral and axial play of the same obviated.

Referring now more in detail to the drawings and to Figs. 1 to 4 thereof, the condenser comprises the stationary plate set S preferably comprising a unitary construction obtained by a die casting process and a

rotatable plate set R also of a unitary construction, the plates of one plate set being arranged in alternate relation with respect to the plates of the other plate set as is common in condensers of this type, the stationary plate set S being carried by a support including the end insulating plates 10 and 11 which may be made, for example, of molded bakelite or the like, the stationary plate set being secured to the end plates as

by means of the sets of spaced securing elements 12 and 13 respectively insertible through suitable bores in the end insulating plates and receivable by suitably tapped bores in the stationary plate set or unit, as

will clearly appear from the drawings, the rotatable plate set or unit R having the shaft 14 being also mounted in the end plates 10 and 11 by means of conical and resilient bearings. In the preferred construction

the manner of mounting the shaft 14 of the rotor R includes the provision of a fixed or adjustable bearing for one end thereof and a resiliently mounted bearing for the other end thereof, preferably both

bearings providing conical seats for the corresponding shaft ends. Referring for example to Fig. 1 of the drawings, the plate 11 is provided with an adjustable externally threaded bearing element 15 adjustable in an

internally threaded metallic insert 16 secured to the plate 11 during the molding of the same, the adjustable bearing being locked in any adjusted position as by means of the set

screw 17 movable in the insert 16, the said bearing element 15 being provided with a tapered or conical seat 18. For cooperation with this conical bearing 15, the shaft 14 is provided at its upper end with a complementary tapered portion or shoulder 19 receivable by the conical seat 18 of the bearing

15. The taper of both the shoulder 19 and the seat 18 may be made the same, the preferred construction, however, including the tapering of these parts in different degrees

or amounts, as will be detailed hereinafter. In a similar manner the other end plate 10 is provided with a conical bearing element 20

provided with a tapered or conical seat or shoulder 21 cooperating with a correspondingly tapered or conical shoulder or seat 22

provided in the lower end of the rotor shaft 14. Although in the preferred construction the conical bearing element 20 comprises the male member with the conical seat 22 of

the shaft the female member, it will be understood that the male member may be provided in either the bearing 20 or the shaft

14. The lower bearing element 20 of my invention is mounted so as to be forced

against the shaft 14 and to resiliently urge the same in the opposed bearing element 15. To accomplish this, in the form disclosed in

Figs. 1 to 4 of the drawings I show the conical bearing element 20 carried by a

125

130

135

140

145

150

155

160

resilient element or spring 23, the latter attached or anchored to the insulating plate 10 as by means of one or more securing elements 24 and 25 receivable by threaded metallic inserts 26 and 27 attached to the insulating plate 10. The bearing element 20 may be secured to the spring 23 as by means of the threaded shank 28 formed preferably integrally with the conical bearing 20, and a nut 29 receivable by the shank 28. For mounting the condenser the front plate 11 may be provided with the spaced bosses 30 each preferably housing a threaded insert 31 for receiving securing elements 32 for mounting the condenser on any suitable support 33; and for rotating the movable plates the shaft 14 of the rotor is provided with the reduced spindle portion 34 adapted for receiving the dial and knob 35. With the provision of this construction, it will be seen that in any position of the rotor R and during rotation of the same, the shaft 14 is floatingly carried at one end by the spring bearing, and the shaft urged by the action of the spring bearing will be resiliently seated in the opposed end bearings 15 and 20 with all axial and lateral play of the shaft and rotor effectively eliminated while producing uniformity of friction between the parts, rotation of the movable plate set being thus obtainable without that looseness and rolling action of the shaft in the bearings incident to the use of prior condenser constructions.

For the purpose of obtaining a definite and uniform frictional movement of the movable plate set in all condensers in spite of the unavoidable manufacturing variations in the angle of taper of the bearings so as to secure a smooth and even turning and steady balancing of the said movable plate set uniformly in all condensers, the shaft of the rotor is preferably so mounted in the bearings as to provide for and insure a constancy of the radius of frictional engagement between the same and the bearings. This may be effectively accomplished in a manner hereinbefore referred to, by producing an unequal or different degree of taper for the complementary conical shaft and bearing portions, so that the frictional engagement between the same will take place on a line as distinguished from a surface, with the said line forming a curve of constant radius. This is shown particularly in Figure 8 of the drawings, and referring to this figure I show the shaft 14' provided at one end with a tapered shoulder 19' cooperating with the conical bearing 15' having the tapered seat 18', the tapered shoulder 19' and the tapered seat 18' being produced at slightly different angles, the tapers being so chosen that the contact between the shaft 14 and the bearing 15' occurs only on a line of constant radius. The difference in taper is somewhat exaggerated in the drawing, it being understood that the difference in the angle of taper may be about one or two degrees. The other end of the shaft 14' is similarly provided with the conical seat 22' cooperating with the conical or tapered shoulder 21' of the conical bearing element 20', the taper here being also so produced as to form a line contact bearing of constant radius. Although I prefer to provide both the shaft and the bearing element 75 with a straight sided taper as shown in the drawings, it will be apparent that other contours may be equally feasible for producing the line contact of uniform radius. With the particular construction shown, moreover, I am enabled to secure a large radius of contact, this being more desirable to permit of a proper balancing of the movable plate set with the aid of a lighter spring than would be needed with a smaller frictional radius. 80

In a condenser of the variable type where the rotor plate set is supported and acted upon by a resilient element or spring device and where proper electrical and mechanical behaviour of the condenser is dependent upon the characteristics and action of the spring, the spring must be relied upon to fulfill a number of desirable conditions. For example, in order to prevent slight variations in the movement or length of parts from seriously changing the tension of the spring and effecting a permanent set therein, the normal deformation thereof must be large, requiring a relatively thin spring having a long effective stress path. In a small condenser of the order of 0.001 microfarads, however, the space limitations prevent the employment of long springs. A desideratum, therefore, is to provide a spring having combined a long effective stress path and compactness. Moreover, in order to perform proper service on a movable condenser unit to effectively take up lateral and axial play thereof, the spring should be constructed to give relatively heavy pressure. Furthermore, in order to prevent any liability of tilting of the shaft and rotor plates so that non-parallelism of the stator and rotor plates with consequent danger of short circuiting at the edges may be avoided, it is highly desirable to provide a spring the force of application of which is exerted directly axially of the rotor shaft. To attain all these ends, my present invention includes the provision of a resilient means having a point of application active on the rotor shaft and anchored to a stationary support of the condenser, with the said resilient means having a stress path substantially greater than the distance between the point of anchor and the point of application, with the resilient means moreover so constructed as to be arranged symmetrically with respect to the point of application. To accomplish this, in the preferred embodiment of my invention I make use of and employ the spring device 100

120

125

130

23 heretofore referred to and shown particularly in Figs. 1 to 3 of the drawings, the said spring device conveniently taking the form of a sheet metal disk provided with the 5 substantially parallel elongated slots *a* and *b* subdividing the disk into a central portion *c* attached to the shank 28 of the bearing element 20 and active thereon to produce the spring pressure, and exterior portions *d* and 10 *e* anchored at spaced points to the insulating plate 10 as by means of the securing elements 24 and 25 heretofore referred to, the construction being such that a plurality of stress paths are active from each point of 15 anchor to the point of application of the spring with each stress path such as indicated by the dotted line *w* in Fig. 3 substantially greater than the distance between a point of anchor and a point of application. Moreover, it will be noted that the stress paths are 20 symmetrically arranged about an axis of the rotor shaft so that the force applied to the shaft is directly axially of the same. It will be seen, furthermore, that by providing a 25 plurality of stress paths, here four numbers, a strong effective spring pressure active on the rotor shaft is obtained.

For the purpose of producing an efficient electrical connection to the rotor plate set 30 and to the shaft thereof, my invention further comprehends a construction in which the electrical connection is made directly from the shaft to a connecting terminal without the intermediation of the spring or any 35 other member, this producing a structure in which the liability of open circuiting due to looseness between the parts is reduced to a minimum and effective electrical contact is obtained. To these ends the connection to 40 the rotor shaft 14 is made directly by way of the conical bearing element 20, and referring to Figs. 1 to 3 of the drawings, I show the shank 28 threaded to receive a binding nut 36, the two constituting a binding post unitary with the conical bearing. For providing 45 for electrical connection to the stationary plate set *S*, said plate set may be provided with the threaded shank 37, forming in conjunction with the lock nut 35 and binding nut 39 a second connecting terminal.

As before mentioned, the rotor and stator plate sets of my condenser, each of which may be provided with one or more plates, are 50 preferably made of a unitary construction and preferably obtained by casting the same as by a die casting process. In casting the rotor plate set, I have found it very desirable in order to obtain strong and durable end bearings and a reinforced construction to 55 cast the unitary plates of the rotor about a central spindle which in the resulting construction forms the shaft 14 of the rotor, the said spindle or shaft being made of a metal different from and having a higher 60 melting point than the metal forming the

unitary plates of the rotor. To this end the rotor comprises the shaft 14 made preferably of steel about which is cast the plate unit or set 40. For the purpose of effectively securing the plate unit or set 40 to the shaft 14, 70 the shaft is preferably provided with a roughened portion 41 at a point intermediate its length, as clearly shown in Fig. 1 of the drawings. To facilitate flow of the metal during casting of the movable plates, and to 75 provide a more rigid rotor unit, the intermediate portion of the shaft 14 may be reduced as shown at 42 in Fig. 9 of the drawings, the reduced portion being provided with the roughened or knurled section 41' to prevent 80 the turning of the casting on the shaft.

For the purpose of limiting axial movement of the shaft against the action of spring 23 to prevent abnormal deformation thereof and to prevent short circuiting of 85 the plates, the shaft 40 is preferably extended to provide the shoulder 40' which cooperates with plate 10 to act as a stop to limit such axial motion, the normal clearance between the plate and shoulder being slightly less 90 than the clearance between adjacent plates.

In a condenser of the variable type, it is highly desirable to provide for a small minimum capacity when the plates are out of 95 capacitive relation with each other, and to further provide for a gradually increasing rate of increase in capacity as the movable plates are rotated into capacitive relation with the stationary plates, and to provide for a maximum capacity when the plates are in 100 maximum capacitive relation with a maximum economy of space. To accomplish these ends, my present invention includes a construction in which the stationary and movable plates are cut away at one side only 105 of the axis of the same, with the construction such that the movable and stationary plate sets when in full capacitive relation with each other are cut away at the same side. This is fully shown in Fig. 4 of the drawings, 110 and referring to this figure it will be seen that a plate of the rotor *R* differs from a substantial semi-circle by being cut away along the line 43 at an angle to a radius of the plate, the cut-away being therefore directed 115 inwardly of the plate with the deepest portion of the cut-away at the central part of the plate, and a plate of the stationary plate set *S* is similarly cut away at the corresponding side along a line 44 also preferably at an 120 angle to a radius of such plate. With this construction a small minimum capacity is obtained, a gradually increasing rate of increase in capacity is effected as the rotatable plates are moved into capacitive relation 125 with respect to the stationary plates, and a maximum capacity is obtained combined with a maximum economy of space.

Referring now to Figs. 5 to 7 of the drawings, I show a modification of my invention 130

in which the rotor R' provided with the shaft 45 is suitably journaled in end plates 45 and 47 which in this instance are full circular plates as contradistinguished from the form shown in Figs. 1 to 4, the said end plates being provided with the conical bearing elements 48 and 49 similar to the conical bearing elements heretofore described with reference to Figs. 1 to 4. In the modified construction, the stator set of plates S' is fixedly supported on the end plate 47 as by means of the symmetrically spaced securing elements 50, the stationary plate casting being provided with the oppositely positioned extending arms 51 (one of which appears in Fig. 5) providing the spaced bosses or posts 52 for receiving the securing elements 50, the said stationary casting S' being floatingly or resiliently mounted on the opposed end plate 46 as by means of the spaced securing elements 53 receivable by and secured to the spaced bosses 54 provided in the extending arms 55 integral with the said stationary plate casting, the said securing means 53 being insertable through orifices 56 provided in the plate 46, a resilient element such as a compression spring 57 anchored at one point to the supporting plate 46 and at another point to a washer 58 engaging the head of the securing means 53 being provided for each securing means for exerting a balanced tension on the plate 46 to produce the desired resilient mounting of the rotor plate set R' . In this form of my invention, therefore, as in the form shown in Figs. 1 to 4, resilient and conical bearings are provided for taking up all lateral and axial play of the rotor shaft. In this form of the invention also the bearing element 48 may constitute the connecting terminal or binding post for the rotor, and to this end the bearing element includes the threaded shank 59 receiving the thumb or binding nut 60. The connecting terminal or binding post for the stationary plate set S' is shown in Fig. 6 of the drawings, the binding post 61 connected to the stationary plate casting S' being provided, the end plate 46 being provided with a suitable cut-out portion 62 through which the binding post extends.

In the manufacture and assembling of condensers, I have found that the end insulating plates which are made from a molding insulating compound such as bakelite suffer an unavoidable and non-uniform shrinkage while cooling, making it impossible to provide the securing-means-receiving orifices therein during molding with sufficient precision to secure proper registration of the plate sets thereon. To avoid this difficulty recourse had to be had to drilling instead of molding the orifices, this latter expedient, however, adding an additional operation with the resulting increase in the cost of production of the condenser. In order to avoid an increase in cost while at the same time providing for proper registration of the condenser parts, the present invention includes the molding of elongated orifices on the end plates so arranged as to compensate for any differential contraction or expansion of the parts taking place during the process of manufacture, while still permitting the obtaining of proper alignment and centered positioning of the end plates on the condenser plates castings during assembly. To this end, referring to Fig. 10 of the drawings, the orifices 63, 64 and 65 in both of the end plates such as the rear end plate 10' are elongated and are disposed approximately radially of the plate 10', the arrangement being such that the direction of bodily shift of the orifices will be mainly along the direction in which they are elongated, so that the center of the bearing will not be shifted seriously, and so that a change in the distance between the orifices which would prevent assembly entirely if the same were round and of the correct diameter to fit the securing means received thereby, will have no detrimental effect in effecting interregistration of the parts. The arrangement of the elongated orifices is furthermore such that the two upper orifices 63 and 65 fix the position of the plate vertically and rotatably with respect to the stationary plate set, and the lower orifice 64 fixes the position of the plate horizontally thereon. A definite and centered position is thereby obtained while permitting or compensating for the contraction of the molded end plate taking place during manufacture.

It is also desirable to avoid depending upon the securing screws for registration and centered positioning of the parts, since this necessitates precision in the making of the securing means greater than the usual tolerance allowed therein, and since furthermore the securing means may be bent under the stress of forcing them into inexact registered orifices in the plate with the resulting inexact alignment and unnecessary stresses applied to the parts. I have therefore found it desirable to provide for interregistering means independent of the securing means, such interregistering means being applicable to either round drilled holes or elongated molded holes in the end plates. This is shown, for example, in Figs. 11 and 12 of the drawings; and referring to these figures the preferred construction includes the provision of interregistering mortise and tenon means in the end plates and stationary plate set, the preferred construction including the provision of tenon members or teats 66 provided in the end plate such as the end plate 11' cooperating with mortises or recesses 67 provided in the spaced posts 68 of the condenser casting. The mortises and tenons are preferably tapered or made coni-

cal as shown, and the mortises are preferably elongated and arranged approximately radially of the casting as clearly shown in the drawings, this to the end of compensating for any differential movement between the parts taking place during manufacture. As shown in Figs. 11 and 12, the securing elements such as 13' are threadedly received by the posts 68 and are receivable by enlarged orifices such as 63', 64' and 65' which preferably are elongated as described.

For the purpose of minimizing losses due to imperfect dielectrics in the electrostatic field of the condenser, the spring which supports the rotor may be mounted on the end plate as shown in Fig. 14 of the drawings. As shown in this figure the supporting spring 23' is attached to the interior, as distinguished from the exterior side of the end plate 10², by means of the securing screws 24' and 25', this to the end of removing the dielectric offered by the end plate 10² from the electrostatic field between the spring 23' and the stator plates S'. The spring 23' carries the conical bearing 20' and the integral binding post 28', a spacing sleeve 69 received by the orifice 70 in the plate 10² being provided for spacing the elements of the binding post from the spring 23'. In this modification the spring 23' also serves to limit axial movement of the shaft, the space between the spring and the end plate 10² being made somewhat less than the clearance between adjacent plates.

The manner of making and using my improved condenser will in the main be apparent from the above detailed description thereof. It will be further apparent that by the provision of the various improvements and the interrelation thereof, that I have provided a condenser which is subject to simplicity of manufacture, ease of assembly and efficiency of operation, the parts combining to produce a strong, compact and neat condenser unit having the desired mechanical and electrical characteristics.

Although I have shown my device in the preferred forms, it will be apparent that a variety of modifications may be made without departing from the spirit of the invention. It will be apparent, for example, that either plate set may consist of one or more plates, and where I have used in the following claims the expression "plate set", I desire it to be understood to apply to a construction in which either one or more plates is used. It will further be apparent that in lieu of providing a straight taper on the bearing or in the interregistering means, that the contour may be changed and made in a variety of ways without departing from the new results achieved. It will be further apparent, for example, that the resilient supporting means of my invention may be modified in a number of ways without de-

parting from the principle involved therein. It will be also understood that many of the features of my invention, while shown applied to electrical condensers, are equally applicable to other precision instruments where similar problems are involved, such for example as in variometers, variotransformers and the like, and I desire it to be understood that the appended claims are intended to be applicable to such equivalent precision instruments. It will be seen that numerous other modifications may be made without departing from the spirit of the invention defined in the following claims.

I claim:

1. A condenser comprising a stator plate set, a rotor plate set, and means for supporting the rotor plate set for movement relatively to the stator plate set including oppositely acting bearings for the shaft of the rotor plate set, one comprising a tapered bearing for one side of the shaft and the other comprising a spring bearing resiliently carrying the other side of the shaft and floatingly supporting the same axially and laterally and active for continuously urging the same against the tapered bearing, so that both lateral play and axial play of the rotor are simultaneously and automatically taken up at each setting of the same.

2. An apparatus of the class described comprising a stator, a rotor, end plates carried by the stator, and means for supporting the rotor in said end plates, said means comprising a bearing for one side of the rotor shaft carried by one of the end plates, a resilient device supported on the other end plate and provided with a bearing arranged to floatingly carry and support the opposite side of the rotor shaft axially and laterally, the said resilient device being active on its bearing to effect the continuous resilient seating of the rotor shaft in both of the bearings so that both lateral and axial play of the rotor are taken up at each setting of the same.

3. A condenser comprising a stator, a rotor, end plates carried by the stator, and means for supporting the rotor in said end plates including a rotor shaft having spaced tapered bearing portions, a bearing carrier by one of the plates and provided with a tapered seat for one of said tapered bearing portions, a bearing carried by the other plate and also provided with a tapered seat for the other of said tapered bearing portions, and a spring active on one of said bearings to effect the continuous resilient seating of the rotor shaft in both bearings.

4. In a device of the class described, a stator, a rotor, end plates carried by the stator, and means for supporting the rotor in said end plates including a rotor shaft having spaced tapered bearing portions, a bearing

- carried by one of the plates and provided with a tapered seat for one of said tapered bearing portions, a substantially flat-shaped spring device carried by the other end plate 5 and a bearing on said spring device also provided with a tapered seat for the other of said tapered bearing portions, the said spring device being active on its bearing and adapted to effect a continuous resilient 10 seating of the rotor shaft in both of its tapered bearings so that both lateral and axial play of the rotor are taken up at each setting of the same.
5. An apparatus of the class described 15 comprising a stator, a rotor, and means for supporting the rotor for movement relatively to the stator, said means comprising oppositely acting bearings for the shaft of the rotor, one comprising a bearing for one 20 side of the shaft and the other comprising a spring device provided with a bearing resiliently carrying the other side of the shaft and floatingly supporting the same axially and laterally and active for continuously 25 urging the shaft against the first-mentioned bearing so that both lateral play and axial play of the rotor are simultaneously and automatically taken up at each setting of the same.
- 30 6. An apparatus of the class described comprising a stator, a rotor, end plates carried by the stator, and means for supporting the rotor in the end plates including a bearing for one end of the rotor shaft carried by 35 one of the end plates, a spring device anchored at a plurality of circumferentially spaced points to the other end plates, a bearing carried by said spring device floatingly carrying and supporting the other end of said 40 rotor shaft both axially and laterally, the said spring device being active on its bearing to effect the continuous resilient seating of the rotor shaft in both of the bearings so that both axial and lateral play of the rotor are taken up at each setting of the same. 45
7. In a condenser, a stationary plate set, a movable plate set and means for movably supporting the movable plate set comprising a bearing adapted to engage the shaft of the movable plate set and a spring device carried by said stationary plate set carrying the said bearing for floatingly supporting the shaft both axially and laterally. 50
8. In a condenser, a stationary plate set, a movable plate set and means for movably supporting the movable plate set comprising a bearing having a tapered seat adapted to engage the shaft of the movable plate set and a substantially flat-shaped spring device carried by said stationary plate set, the said 55 spring device carrying the said bearing for floatingly supporting the shaft both axially and laterally. 60
9. In a condenser, means for supporting a movable plate set comprising a bearing element having a tapered portion for forming a bearing seat and a shank portion for forming a connecting terminal; and a spring element carrying the bearing element. 65
10. In a condenser, a plate unit, a supporting plate therefor, and means for positioning one on the other comprising a plurality of spaced tenons on the one and a plurality of cooperating spaced elongated mortises arranged approximately radially on 70 the other. 75

Signed New York city in the county of Bronx and State of New York this 31st day of July, A. D. 1922.

BENJAMIN Q. ISLER.
